CLAIM

The ornamental design for a footwear outsole, as shown and described.

DESCRIPTION

FIG. 1 is a bottom perspective view of a footwear outsole showing my new design;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a rear elevational view thereof.

The broken lines immediately adjacent to the solid lines in FIGS. 1, & 3-6 represent the boundary of the design while the broken lines showing the remainder of the sole and a shoe upper illustrate the environment in which the design resides. The broken lines form no part of the claim.
